VEHICLE AIR CONDITIONER

Filed Nov. 8, 1938

UNITED STATES PATENT OFFICE

2,277,962

VEHICLE AIR CONDITIONER

Paul E. Diederich, Detroit, Mich.

Application November 8, 1938, Serial No. 239,536

2 Claims. (Cl. 62—146)

My invention relates to a temperature regulating device for vehicles and more particularly to the cooling of the interiors thereof.

Heretofore efforts in cooling the interior of vehicles have resulted in costly, cumbersome and inadequate appliances combined with engine cooling systems.

The object of my invention is to provide a simple and inexpensive air cooling device to be combined with the hot water heater of a vehicle.

For a better understanding of my invention, reference should be had to the detailed description and claims which follow connection with the accompanying drawing illustrating a preferential embodiment of my invention of which:

Figure 1 is a diagrammatic plan view illustrating the air cooling device in combination with a vehicle hot water air heating system.

Figure 2 is an isometric view of the cooling tank with cover.

Figure 3 illustrates isometric views of the liquid intake box.

Figure 4 is an enlarged sectional elevation view of the intake filter box.

Referring to Figure 1, heater and cooling unit 11, containing a suitable metallic coil or core through which a precooled liquid medium is pumped, is located preferably in the front portion of the vehicle on the dashboard. Flexible conduits 12 and 13 with shut-off valves 14 and 15 provide the interconnecting means for circulating the precooled liquid medium, such as water, through the coils or radiation element in the heater and cooling unit 11. Tank 16 with cork or other suitable insulation 17, in my preferable embodiment, located in the trunk or the compartment of the vehicle retains and stores the liquid cooling medium. Centrally located at the bottom of the tank is the intake box 22, the construction of which is shown in Figure 3, through which the cooling medium is drawn before flowing through the coils in the heating and cooling unit 11. The intake box 22 is provided with an intake tube 19 to which the intake end of the flexible conduit 12 is connected said box being closed on the top with a suitable outlet opening provided for the reception of said intake tube 19 into the inside of said box. The intake box bottom 18 otherwise open to the atmosphere is fitted with an integral coarse screen 20. A fine framed screen 21 removably fits within the intake box bottom 18 and rests upon the top of the coarse screen 20, thereby providing a double screen or filter to keep foreign matter from getting through to the pumps and cooling coil.

Frame screen 21 is removed for cleaning from its resting place by first removing member 22 from the box bottom 18. Closure of the intake box 22 is provided by the screened bottom 20 which fits therein.

Fixed within the tank and always above the liquid level is secured a baffle or ice tray 23 upon which ice or solid carbon dioxide is stored (dry ice).

10 The return conduit 13 is provided on a portion thereof, within the tank 16, with a perforated portion 24 through which the cooling medium such as water is allowed to drip or is sprayed upon the ice held by the tray.

15 By this means the water is cooled through its temporary contact with the ice, whence it falls to the bottom of the tank to be circulated through the aforementioned flexible conduits 12 and 13.

20 Circulation of the cooling water is accomplished in my preferable embodiment by the insertion into the system at any point of an electrically operated pump 25 actuated by the vehicle battery. Said pump consists of four pump units wired with two switches so that either two or four units may be operated depending upon the amount of cooling required. It is recognized, however, that a mechanical operated pump could be used instead.

25 An electric fan 26 in fixed relation to the coils 11 operable by means of a suitable switch (not shown) mounted on the vehicle instrument board provides the means for causing circulation of the air within the vehicle in heat exchange relation with the metallic coils through which the cooling medium is circulated.

30 An overflow pipe 27 centrally located within the tank provides a means of disposal of excess fluid in the tank so that the liquid level is always maintained below the ice tray. By keeping the ice or dry ice out of continued physical contact with the fluid, the ice supply is conserved.

35 Where dry ice is used the overflow pipe provides an exit for the escaping carbon dioxide fumes from the tank.

40 As shown in Figure 2, the drain cock 28 is located at the bottom of the tank.

45 Hingedly mounted upon the tank 16 is an arm 29 which is designed to rest upon the bumper of the vehicle and support the tank when partially removed from the rear compartment for replenishing the ice supply and which rotates upon its hinge and is folded parallel to said tank when the cooler has been filled and is pushed back in the vehicle trunk compartment on stainless steel tracks provided therefor.

It is contemplated by the inventor that the aforesaid cooling system be combined with the conventional air heating hot water system wherein hot water from the engine's water jacket is circulated through the same coil 11 in heat exchange relation to the air of the interior of the vehicle, the air being caused to circulate by means of the same electric fan 26 aforementioned.

The shut off valves 30 and 31 connected with the hot water supply and return conduits to and from the hot water heater from the engine water jacket are manually operable in my preferable embodiment. However, the substitution of other types of valves is contemplated as within the scope of my invention, such as electric solenoid valves controlled from instrument panel by a master switch showing positions for heating or cooling.

In Figure 1, the vehicle engine is diagrammatically indicated at 32 with water pump 33, fan 34, and radiator 35. Regular hot water lines indicated at 36 and 37 provide the conventional source of supply of hot water to the coils 11 when it is desired to be used as an air heater.

In hot weather the hot water air heating system for the interior of the vehicle is readily converted into an air cooling device merely by manually closing the cut-off valves 30 and 31. The valves 14 and 15 are then manually opened, and with ice and a liquid medium in the tank, by switching on the pump, and fan, the air cooling system is in operative condition.

Now having fully described my invention herein, reference will be had to the claims which follow for determining the scope hereof.

I claim:

1. In an air conditioner for a vehicle through which is circulated a pre-cooled pumped cooling medium, an insulated liquid storage tank with a cover therefor, a supporting baffle therein upon which ice is placed above the stored liquid medium in the bottom of said tank, an easily cleanable intake filtering box through which the cooling medium is drawn and filtered for circulation, consisting of a removable base portion, within which is framed a coarse screen above the bottom of and providing for communication between the interior of the box and the interior of said tank, and independently framed fine screen removably disposed in said box, and a cover cooperating with said base portion, said box having an outlet opening for connection with a supply conduit, and a tube longitudinally disposed within the top portion of said tank, perforated throughout and closed on one end with the other end open for communication with a return conduit.
2. In an air conditioner for a vehicle, through which is circulated a cooling medium, a storage tank, a supporting baffle therein upon which ice may be placed above a stored liquid medium in the bottom of said tank, an intake filter box disposed within said tank, comprised of a removable base portion within which is framed a coarse screen, a framed fine screen removably disposed in said box, and a cover portion for cooperation with said base portion to form a closed container, an outlet being provided therein for connection with a supply conduit, a perforated return conduit longitudinally disposed within the top portion of said tank, through which the cooling medium on return to the tank is sprayed over the ice held on said baffle.

PAUL E. DIEDERICH.
